FIG. 1.

FIG. 2.

Inventors

PHILIP FELDMAN.
REYNELLE G. H. CORNISH.

By *Clarence O'Brien*
Attorney

UNITED STATES PATENT OFFICE

PHILIP FELDMAN, OF JAMAICA, AND REYNELLE G. H. CORNISH, OF RICHMOND HILL,
NEW YORK

GARMENT SUPPORTER

Application filed September 8, 1931. Serial No. 561,784.

This invention relates to improvements in garment supporters, and has particular reference to a device for preventing the upward riding of the front of a shirt above the top 5 of the trousers of a wearer, and to further assist the belt or suspenders in preventing sagging of the trousers at the front thereof.

Another object of the invention is to provide a device of the character mentioned 10 which is entirely concealed when in worn position and which is comfortable in that it does not interfere with the free body movements of the wearer.

A further object of the invention resides 15 in the provision of a garment supporter for the above mentioned purposes which is simple of construction, inexpensive of manufacture, easy to apply to or remove from its worn position, and which is strong and durable for the purposes intended.

With these and other objects in view, the invention resides in the certain novel construction, combination and arrangement of parts the essential features of which are hereinafter fully set forth, are particularly pointed out in the appended claims, and are illustrated in the accompanying drawings, in which,

Figure 1 is a perspective view of our improved garment supporter, showing the same in operative position for connecting the lower end of a shirt to the upper or top end of a pair of trousers, the front walls of the trousers being open in order to reveal the supporter,

Figure 2 is a vertical longitudinal sectional view through the garment supporter and showing the same in operative position,

Figure 3 is a rear elevational view of the garment supporter per se, and;

Figure 4 is a top plan view of the same.

Referring to the drawings by reference characters, the numeral 10 designates our improved garment supporter in its entirety 15 which comprises a shirt attaching element 11 and a button attaching element or member 12. The element 11 is constructed from a single piece of flat metal and includes a body 13 having its upper edge bent over to provide a flange 14 which is disposed in spaced relation

with respect to the body, the lower edge of the flange being provided with teeth 15. The body 13 is provided with an elongated slot 16 which extends inwardly from one of the side edges thereof and which slot is disposed on a plane just above the edges of the teeth 15. Extending from the lower edge of the body are spaced aligned ears 17 provided with openings 18 for a purpose to be presently explained. We appreciate that various garment supporters have been constructed in which the shirt attaching member is constructed along the lines above set forth but our invention resides in the combination of such an attaching member with the construction of 60 button attaching element 12 now to be fully described.

The button attaching member 12 is constructed of a single length of stiff bendable wire which is bent midway between its ends 70 to provide a loop 19 which loop is open in a direction facing the shirt attaching member 11. The wire adjacent the open end of the loop is bent outwardly at an angle to provide outwardly diverging walls or portions 20, which provide the open end of the loop with an outwardly flared mouth 21. The opposite end of the wire is thence bent outwardly to form arms 22 while the terminal ends of the wire are bent at an angle 80 with respect to the arms 22 to form attaching eyes 23, which eyes pass through the openings 18 in the respective ears 17 of the body plate 13. It will therefore be seen that the button attaching member 12 is pivotally or swingingly connected to the shirt attaching member 11 and which is for a purpose to be herein presently explained.

In Figure 1 of the drawings we have clearly illustrated our invention as applied to the front of a shirt A and in attaching the supporter to the shirt, the plate or body 13 is held in a substantially horizontal position or in a position with the lower edge facing upwardly. The edge of the shirt front passes into the elongated slot 16 until it strikes the closed end of the said slot, after which the plate or body 13 is turned downwardly which causes the teeth 16 to grip the fabric of the shirt. The letter B designates 85 100

the upper front portion of a pair of trousers while fixedly attached to the inside of the same adjacent the fly opening is a button C which may be stitched in position or may 5 be of the bachelor type for use in connection with trousers in which no inside button is provided. Assuming that the shirt attaching member 11 has been inserted upon the edge of the shirt and is in gripping position 10 whereupon the button attaching member 12 may be swung to a vertical position and the pants lifted so that the stitching connecting the button with the pants fabric passes through the outwardly flared mouth 21 of the loop 19. The opposite walls of the loop 19 adjacent the flared mouth extend inwardly as at 24 to provide a restricted passage which 15 prevents the accidental disengagement of the stitching from the looped member when in an inserted position therein. Although we 20 have mentioned that the member 12 is not connected to the button until the shirt attaching member 11 has been moved to gripping engagement with the shirt, nevertheless 25 the button attaching member may be connected with the button prior to the movement of the shirt attaching member to clamping position in order that correct adjustment of the device may be made relative to the shirt. 30 From the foregoing description, it will be seen that we have provided a garment supporter which may be quickly and easily attached to the inside button of a pair of trousers and to the front edge of a shirt and 35 which will prevent the shirt from riding above the top edge of the trousers and also coact with the suspenders or belt of the wearer in supporting the front of the trousers against sagging. By pivotally connecting the button attaching member 12 with the shirt attaching member 11, a flexible joint is 40 provided which permits the forward bending of the wearer without causing the supporter pushing inwardly against the abdomen or body of the wearer. 45 While we have shown and described what we deem to be the most desirable embodiment of our invention, we wish it to be understood that various changes as come within the scope 50 of the appended claims may be resorted to if desired.

Having thus described the invention, what is claimed as new and what it is desired to secure by Letters Patent of the United States, is;

1. In a garment supporter in which a slotted plate provided with gripping teeth adjacent the slot is adapted to be inserted 55 upon the edge of a shirt at the front thereof and turned down to cause the teeth to grip, a button attaching member constructed of a single piece of stiff bendable wire, said wire bent midway between its ends to provide a looped portion, the opposed walls of 60 the looped portion being bent inwardly to

provide a restricted passage at the open end thereof, while the free ends of said wire are extended outwardly in opposite directions and terminate in spaced alined eyes, said eyes passing through openings provided in 70 said slotted plate whereby said button attaching member is swingingly connected to said plate.

2. A garment supporter comprising a flat plate, attaching means formed in said plate 75 by which the same may be detachably connected to a shirt, a button attaching member formed from a single length of stiff bendable wire, said length of wire being bent upon itself midway between its ends to provide a 80 loop open at one end, the wire being bent outwardly at an angle in opposite directions adjacent the open end of the loop to provide an outwardly flared mouth, the free ends of said wire terminating in eyes which pass through spaced openings provided in said plate whereby said button attaching member is swingingly connected to said plate.

In testimony whereof we affix our signatures.

PHILIP FELDMAN.
